UNITED STATES PATENT OFFICE.

WILLIAM H. ENGLAND, OF CHICAGO, ILLINOIS, AND EDWIN H. ALLFREE, OF IRONTON, OHIO.

DERAILER.

1,251,205.

Specification of Letters Patent. Patented Dec. 25, 1917.

Application filed March 3, 1917. Serial No. 152,432.

To all whom it may concern:

Be it known that we, WILLIAM H. ENGLAND and EDWIN H. ALLFREE, citizens of the United States, residing at Chicago, in the county of Cook and State of Illinois, and Ironton, in the county of Lawrence and State of Ohio; have invented a new and useful Improvement in Derailers, of which the following is a specification.

10 Our invention relates to derailers constructed to derail a train moving in either direction along the track into engagement with the derailler.

As a preface to a description of our invention, it may be stated that it is highly desirable that the wheel-deflecting surfaces of the derail, forming the portion thereof which forces the wheel from the track be made as low as possible and that they extend 15 at a relatively slight angle to the plane of the rail to which it is applied, inasmuch as the greater the angle at which the said deflecting surface extends relative to the plane of the rail, the greater the thrust exerted 20 against the derail in the derailing operation, with the manifest disadvantages.

As double-end derailers have hitherto been provided they have either presented the disadvantage of the derailing surfaces being 25 at too great an angle to the plane of the rail for the practical and safe operation of the structures, or, where the angle at which these deflecting surfaces extend relative to the plane of the rail, is less, and more nearly 30 as desired, the derailler is of undue length, rendering it very expensive to manufacture and more difficult to operate.

Our primary object is to provide a construction of double-end derailler wherein its 35 derailing surfaces may be caused to extend, relative to the plane of the rail, at substantially the same angle as in the case of single-end derailers of the long derailing surface type, without providing the structure of substantially greater length than in the case of 40 the single-end derailing, or of undue height.

Referring to the accompanying drawings:

Figure 1 is a plan view of a derailler constructed in accordance with our invention, 45 the derailler being shown as supported in position on the ties of a road-bed, adjacent a railway rail.

Fig. 2 is a section taken at the line 2 on Fig. 1 and viewed in the direction of the

arrow, this view showing our improved derailler in end elevation.

Fig. 3 is a view in side elevation of the derailler shown in Fig. 1 together with the underlying rail on which it is seated, the structure being viewed from the right-hand side of Fig. 1; and

Figs. 4 and 5, sections taken at the lines 4 and 5, respectively, and viewed in the direction of the arrows.

The derailler block of the device is represented at 6, this block being provided with a shank-portion 7 of reduced length, which extends between spaced uprights 8 carried by a base-plate 9 which in practice would be spiked, as indicated at 10, to the ties 11 supporting the rail, as, for example, that illustrated at 12, and adjacent to which the derailler is to be located, the derailler-base 9 being located at the inner side of the rail and the block 6 being pivotally supported on the base 9, as through the medium of a pivot-bolt 13 which extends through the uprights 8 and the shank-portion 7 of the block, permitting the latter to be moved into and out of a position in which it rests upon 70 the head of the rail, in accordance with common practice, the block 6 being shown as connected with a rod 14 journaled at 15 in a lug 16 extending laterally from the shank 7 and forming a connection with a signaling device (not shown) when the derail is operated by hand.

According to our invention the upper surface of the block 6, considering it in a position in which it is seated upon the rail 12, is of such form as to present more or less abrupt shoulders 17, 18, 19 and 20, the shoulders 19 and 20 being in substantial alinement and the shoulders 17 and 18 in substantial alinement. The shoulders 17 and 19 extend 95 at substantially the same angles to the plane of the rail 12, and their ends adjacent the ends of the block 6 are so located that the flange of a wheel traveling along the rail 12 and riding up on the inclines 21 at the end 100 of the block 6 will strike against the shoulder 17 or 19, as the case may be, depending upon the direction in which the wheel is moving when it strikes the block. As shown in Fig. 3, the shoulders 17 and 19 are disposed in substantially the same horizontal plane and meet at the point 22, which, by reason of the relatively long angle at which

these shoulders extend relative to the plane of the rail, is at a point closely adjacent the innermost side of the head of the rail 12. The shoulders 17 and 19 serve, in conjunction with the shoulders 18 and 20, respectively, as hereinafter fully explained, as deflecting surfaces for carrying the flange of the wheel from the inner side of the head of the rail 12 to a point beyond the outside of the rail, to effect the derailing operation. The shoulders 18 and 20, as will be readily understood from the drawings, extend from the point of convergence of the shoulders 17 and 19 adjacent the inner side of the rail to points closely adjacent the outer side of the rail, and are in a plane below that in which the shoulders 17 and 19 extend adjacent the point of convergence of the latter, the upper surface of the block 6 lying within the angle formed between the shoulders 18 and 20, being preferably dished, as represented in the drawings.

Assuming the derailer to be shown in the position illustrated in Fig. 1 and a train to be approaching the lowermost end of the derailer in this figure, the tread of the wheel would ride upon the incline 21 and the flange of the wheel upon the portion of the block between the end of the shoulder 19 and the surface 21, this surface, which is in the form of a channel 23 and is duplicated at the opposite end of the structure at 24, being flanked by the shoulder 19 at one end of the block 6 and the shoulder 17 at the other end. The flange of the wheel in the forward movement of the latter by running against the surface 19 would be deflected to the right in Fig. 1, and upon passing the point 22 would drop into engagement with the shoulder 20, which latter, forming in effect a continuation of the deflecting surface 19, would serve to continue to force the wheel, by engaging with its flange, to the right in Fig. 1, finally causing the flanged wheel to run off the derail and drop to the outside of the rail.

Inasmuch as the ends of the derail block are duplicates, the engagement of the derail by a wheel moving in the opposite direction and approaching the block 6 from the upper end in Fig. 1, would be forced laterally across the rail by movement to the right in Fig. 1 in engaging the deflecting surfaces 17 and 18.

It will be readily understood from the foregoing that by constructing a derailer block in accordance with our invention the derailer need not be substantially longer nor higher than a single derailer presenting a deflecting surface extending at the same angle to the plane of the rail. In other words, by our invention we are enabled to provide for the deflecting of a vehicle moving in either direction over the track by a derailer which is substantially no greater in

length or height than a single derailer presenting the same slight angle between its deflecting surface and the plane of the rail, thus presenting all of the advantages of derailing by means of a relatively slightly inclined derailing surface, by the provision of a relatively compact and inexpensive construction and one presenting the maximum ease of operation.

While we have illustrated and described a particular construction in which our invention is embodied, we do not wish to be understood as intending to limit it thereto, as the same may be variously modified and altered without departing from the spirit of our invention, it being our intention to claim our invention as fully and completely as the prior state of the art will permit.

What we claim as new and desire to secure by Letters Patent is—

1. A derailer formed of a block adapted to rest upon a rail and having derailing surfaces for engaging the flange of a wheel in moving into engagement with the block from either direction, respectively, said derailing surfaces intersecting each other between their ends with portions of each thereof extending at opposite sides of said intersection.

2. A derailer formed of a block adapted to rest upon a rail and having derailing surfaces for engaging the flange of a wheel in moving into engagement with the block from either direction, respectively, said derailing surfaces intersecting between their ends, and the portions of said derailing surfaces beyond said intersection, adjacent one side of the block, being located in a plane below that in which the other portions of said derailing surfaces adjacent said point of intersection, extend.

3. A derailer formed of a block adapted to rest upon a rail and having derailing surfaces for engaging the flange of a wheel in moving into engagement with the block from either direction, respectively, said derailing surfaces intersecting between their ends, the upper surfaces of the ends of said block at the portions thereof directly overlying the rail, being inclined upwardly from their extremities toward the middle of the block for engagement with the tread of the wheel, and said block intermediate said upper surfaces and portions of said derailing surfaces adjacent the ends of the block, being channeled to receive the flange of the wheel.

4. A derailer formed of a block adapted to rest upon a rail and having derailing surfaces for engaging the flange of a wheel in moving into engagement with the block from either direction, respectively, said derailing surfaces intersecting between their ends and the portions of said derailing surfaces beyond said intersection adjacent one side of the block, being located in a plane

below that in which the other portions of said derailing surfaces, adjacent said point of intersection, extend, and said block intermediate said upper surfaces and portions of 5 said derailing surfaces adjacent the ends of the block, being channeled to receive the flange of the wheel.

5. A derailer formed of a block adapted to rest upon a rail and having derailing surfaces for engaging the flange of a wheel in moving into engagement with the block from either direction, respectively, said derailing surfaces intersecting between their ends, the lower portions of said derailing 10 surfaces inclining downwardly toward the side of the block adjacent the outer edge of the rail.

6. A derailer formed of a block adapted to rest upon a rail and having derailing surfaces for engaging the flange of a wheel in moving into engagement with the block from either direction, respectively, said derailing surfaces intersecting between their ends and the portions of said derailing surfaces beyond said intersection, adjacent one side of 20 the block, being located in a plane below that in which the other portions of said derailing surfaces, adjacent said point of intersection, extend, the lower portions of said derailing surfaces inclining downwardly to- 25 30 toward the side of the block adjacent the outer edge of the rail.

WILLIAM H. ENGLAND.
EDWIN H. ALLFREE.
